AUTOMOBILE DIRECTION SIGNAL.

Filed Sept. 24, 1923

Fred L. Rose

By Watson E. Coleman

Attorney

UNITED STATES PATENT OFFICE.

FRED L. ROSE, OF CONCORD, CALIFORNIA.

AUTOMOBILE DIRECTION SIGNAL.

Application filed September 24, 1923. Serial No. 664,470.

To all whom it may concern:

Be it known that I, FRED L. ROSE, a citizen of the United States, residing at Concord, in the county of Contra Costa and State of California, have invented certain new and useful Improvements in Automobile Direction Signals, of which the following is a specification, reference being had to the accompanying drawings.

10 This invention relates to automobile direction signals and has for a particular object thereof the provision of a device including a rotatable pointer which by operation thereof will indicate the intention of the 15 driver to turn in the direction of such turn or his intention to stop.

20 A further object of the invention is to provide a device of this character, the pointer of which is normally horizontal and 25 which pointer remains horizontal during indication of direction, but which is operable to cause the pointer to assume an inclined position to indicate the intention of the driver to stop.

25 A further object of the invention is to provide a device of this character which is very simple in its construction and operation, which will be very readily applied to the vehicle and which will be durable and 30 efficient in service.

These and other objects I attain by the construction shown in the accompanying drawings wherein for the purpose of illustration is shown a preferred embodiment 35 of my invention and wherein:

Figure 1 is a fragmentary view showing signaling apparatus constructed in accordance with my invention applied to a vehicle, the vehicle being indicated in dotted lines;

40 Figure 2 is a vertical sectional view through the signal, parts being shown in elevation;

Figure 3 is a side elevation, parts being broken away, showing the angular position 45 of the signal;

Figure 4 is a fragmentary side elevation of the tube showing the construction of the slot; and

Figure 5 is a section on the line 5—5 of 50 Figure 2.

Referring now more particularly to the drawings, the numeral 10 indicates a tubular support having adjacent its lower end a flange 11 and having its lower end below 55 the flange threaded, as indicated at 12.

Mounted upon the threaded portion below the fender is a plate 13 which may be secured to the fender flange 14 by means of ears 13^a to hold the support 10 in desired position. The support 10 has rotatably and vertically shiftable mounted therein a shaft 15, the upper end of which is slotted. Into the slot of the shaft extends a flange 16 formed upon an indicator bar 17 and extending longitudinally of such bar. The upper end of this flange is of a width approximately equal to the internal diameter of the tubular support 10 and from such upper end the flange decreases in width downwardly. Adjacent its lower end a pivot 18 extends through the flange and the shaft to pivotally connect the same.

The indicator tube 17 is provided upon one end thereof with an arrow head 19 and at the opposite end with a furcated extension 20 representing the feathering of an arrow. The flange 16 is secured to the tube so that when supported by the pivot 18 thereof the arrow head end of the tube is the heavier and will drop downwardly by gravity. Accordingly, if the shaft be simply rotated the engagement of the upper end of the tubular support with the direction tube 17 will cause the signal to remain in horizontal position. If, however, the shaft 15 be elevated so that the tubular support 10 is removed from the indicating bar 17 this bar will tilt with the arrow end thereof pointing downwardly. The tubular support 10 is provided in the wall thereof with a horizontal slot 21 extending through approximately 180°. At one end the slot is provided with an upwardly angling extension 22. In the slot operates a pin 23 secured to the shaft 15. As long as this pin remains in the slot 21 the indicator bar 17 is engaged by the upper end of the support 10 and is accordingly held horizontal. When the pin 23 is engaged in the extension 22 the shaft 15 is elevated and the support 10 accordingly removed from the bar so that the inclination thereof occurs.

It will be obvious that if suitable means are provided for rotating the shaft 15 the same may be engaged in either the slots 21 or 22 and accordingly the position determined. By stopping the indicator at one end of the slot 21 a "right" turn is indicated, at an intermediate point "straight ahead" is 110

indicated, at the opposite end of the slot 21 a "left" turn is indicated, and in the slot 22 a "stop" is indicated. In the present instance this means for rotating the shaft 15 5 is disclosed as a bevel gear 24 splined to the lower end of the shaft 15 which projects below the lower surface of the plate 14. The pointer 14 is provided with a downwardly 10 extending flange 25 through which extends a stub shaft 26 having upon its inner end a bevel gear 27 meshing with the gear 24. The outer end of this shaft is provided with a joint 27, such as is ordinarily employed for connecting the drives of flexible shafts, 15 which flexible shaft may be extended to the dash of the vehicle and operated with any suitable mechanism. Since the same is not herein claimed by me other than as a means for operating the device, it has been simply 20 disclosed as a pointer 28 operating over a dial 29 having indicia 30 indicating positions of the indicator bar 17.

The lower end of the housing formed by the flange is closed by a plate 31. Through 25 this plate extends a lead wire 32 which passes upwardly through a groove 33 extending longitudinally of the shaft. The indicator bar 17 is tubular and has mounted in opposite ends thereof illuminating elements 34 30 and 35 for the point 19 and tail structure 20 of the arrow. The upper end of the pointer 32 is connected with a pointer extending through this tube and engages at its opposite ends with the contacts of the illuminating elements 34 and 35. From the foregoing 35 it is believed to be obvious that the simple structure hereinbefore set forth is capable of giving all the indications which are necessary in signaling the intentions of the driver of an automobile. It will furthermore be obvious that the structure hereinbefore set forth is capable of some change 40 and modification without in any manner departing from the spirit of my invention 45 and I accordingly do not limit myself to such specific structure except as hereinafter claimed.

I claim:—

1. In a direction signal, a pivotally 50 mounted unbalanced signal bar adapted to be raised and lowered, a support upon which the bar rests when in lowered position to thereby maintain the bar in horizontal position, and means for rotating the bar including a part elevating the bar upon rotation thereof to a predetermined degree to thereby disengage the bar from the support and permit tilting thereof.

2. In a direction signal, a pivotally 60 mounted unbalanced signal bar adapted to be raised and lowered, a support upon which

the bar rests when in lowered position to thereby maintain the bar in horizontal position, and means for rotating the bar including a shaft to which the bar is pivoted 65 and which is rotatable and shiftable upon its longitudinal axis, and a connection between said bar and support whereby rotation of the bar to a predetermined point elevates the shaft to thereby disengage the bar from 70 the support and permit tilting thereof.

3. In a direction signal, a pivotally mounted unbalanced signal bar adapted to be raised and lowered, a support upon which the bar rests when in lowered position to 75 thereby maintain the bar in horizontal position, and means for rotating the bar including a shaft to which the bar is pivoted and which is rotatable and shiftable upon 80 its longitudinal axis, and a connection between said bar and support whereby rotation of the bar to a predetermined point elevates the shaft to thereby disengage the bar from the support and permit tilting 85 thereof, the engagement between said support and shaft comprising a pin carried by one thereof and operating in the horizontal slot formed in the other thereof, the slot having an angular extension at one end thereof.

4. In a direction signal, a pivotally 90 mounted unbalanced signal bar adapted to be raised and lowered, a support upon which the bar rests when in lowered position to thereby maintain the bar in horizontal position, and means for rotating the bar including a shaft to which the bar is pivoted and which is rotatable and shiftable upon 95 its longitudinal axis, and a connection between said bar and support whereby rotation of the bar to a predetermined point elevates the shaft to thereby disengage the bar from the support and permit tilting thereof, the engagement between said support and shaft comprising a pin carried by one 100 thereof and operating in the horizontal slot formed in the other thereof, the slot having an angular extension at one end thereof, said support being tubular and forming a 105 housing for said shaft.

5. In a direction signal, a rotatable and 110 longitudinally shiftable support, means for rotating the support, means whereby said support is longitudinally shifted upon a predetermined rotation thereof, a signal pivoted upon the support at an angle thereto and 115 rotating therewith, and means whereby the angle of the signal to the support is altered when the support is longitudinally shifted.

In testimony whereof I hereunto affix my 120 signature.

FRED L. ROSE.
